DESIGN FOR A COMB HOLDER OR SIMILAR ARTICLE

Yoshio Fushimi, Chicago, Ill.

Application May 5, 1941, Serial No. 100,786

Term of patent 7 years

To all whom it may concern:

Be it known that I, Yoshio Fushimi, a subject of the Emperor of Japan, residing at Chicago, in the county of Cook and State of Illinois, have invented a new, original, and ornamental Design for a Comb Holder or Similar Article, of which the following is a specification, reference being had to the accompanying drawing, forming a part thereof.

Fig. 1 of the drawing is a front elevational view of a comb holder embodying my new design.

Fig. 2 is a left side elevational view of the same.
Fig. 3 is a top plan view of the same.
The left and right sides of the design are alike.

I claim:

The ornamental design for a comb holder or similar article, substantially as shown and described.

YOSHIO FUSHIMI.
